UNITED STATES PATENT OFFICE.

CHARLES F. DOEBLER, OF AUSTIN, TEXAS, ASSIGNOR TO PERFECT POINT PENCIL CORPORATION, OF NEW YORK, N. Y., A CORPORATION OF DELAWARE.

PENCIL.

Application filed March 11, 1921. Serial No. 451,467.

This invention relates to pencils. More specifically it relates to pencils of the type in which the crayon may be fed or forced from the body of the pencil.

5 A type of pencil, now well known, comprises a barrel provided with a member having a bore in which a lead is frictionally held. In this type of pencil the lead may be forced from the pencil by causing longitudinal movement of a rod or other follower. Friction between the side walls of the bore and the lead is relied on to prevent the latter from dropping from the pencil. If a lead employed in refilling such a pencil is 15 smaller in diameter than that for which the lead-receiving bore is designed the lead slips down from time to time which is extremely annoying and leads to breakage of the lead. Furthermore, even when leads of uniform 20 diameter are employed, the use of such a pencil is practically limited to comparatively hard leads. If a soft lead or crayon (such as indelible crayon) is employed it becomes so worn in the normal feeding operation 25 that before any considerable amount has been consumed the above referred to objectionable slipping begins.

One of the principal objects of the present invention is to overcome the above mentioned objections; i. e., to provide a pencil of the type indicated in which a soft lead, or a lead considerably under-size, or a colored crayon such as an indelible crayon may be employed without objectionable 35 slipping.

Another object is to provide a pencil which is simple in construction in view of the functions performed. Other objects and advantages will become apparent as the invention is hereinafter disclosed.

Referring to the drawings which illustrate what I now consider a preferred form of my invention:

Figure 1 is an elevation partly in section of my improved pencil.

Fig. 2 is a top plan view of the same.

Fig. 3 is a section on the line 3—3 of Fig. 1.

Fig. 4 is a fragmentary detail elevation 50 showing a form of means for readily determining the amount of lead or other crayon in the lower portion of the pencil.

The pencil illustrated comprises a barrel or outer casing 1 provided with a tip 2 screw-threadedly or otherwise detachably

secured thereto. The said tip is provided with a bore shown internally threaded at its upper portion, tapering or converging at its intermediate portion and terminating in a reduced portion of large enough diameter 60 to permit passage therethrough of the largest diameter lead intended to be employed in the pencil. A sleeve or guide tube 3 internally bored to a diameter at least equal to the diameter of the largest lead to 65 be employed, is provided with a tapering end 4, the apex angle of which is preferably slightly greater than that of the tapering bore in the tip 2. The said member 3 is externally threaded at 5 to co-operate with 70 the internal threads of the said tip 2. The tapering end of the member 3 is provided with one or more longitudinal slits 7 as clearly shown in Fig. 3.

By virtue of the structure thus far described a lead or crayon 6 mounted in the bores of the members 2 and 3 will be frictionally held against dropping from the pencil even though the diameter of the lead may be under standard either due to wear 75 or lack of uniformity of manufacture. If it is found that any crayon slips out of the pencil at times when no feed is taking place the frictional pressure may be increased by the following operation.

The tip 2 together with its sleeve or tube 3 may be removed by unscrewing the former from the barrel 1. The member 3 may then be adjusted toward the tip 2 by relative turning of these members in the proper direction. If the parts 2 and 3 are moved towards each other the somewhat resilient tapering end portions of the member 3 will be forced or wedged inwardly to exert a greater pressure on the crayon. The parts 80 should preferably be so adjusted as to prevent the lead from dropping from the pencil but nevertheless not so tight as to impose 85 too great impedance to feeding of the lead as hereinafter described. A lock nut 8 or other suitable means may be provided for holding the parts 2 and 3 in their adjusted position. The adjustment having been effected, the tip 2 may again be screwed into 90 the barrel.

The feeding mechanism which I prefer, at present, to employ may be constructed substantially as follows: A follower rod or wire externally threaded at its upper end, 95 as indicated at 10, is provided with a sub- 100

stantially cylindrical portion 9 of such diameter as to be freely movable in and through the internal bore of the guide member 3. The rod 10 is constrained against 5 rotation with respect to the casing 1 by means of a longitudinal key way 13 into which a pin 12 (serving as a key) extends, the pin being mounted in a block 11 secured to the casing 1 by one or more rivets or other 10 suitable means such as soldering. The block 11 is provided with an opening through which the rod 10 is freely movable in an axial or longitudinal direction. A nut 16, internally threaded to co-operate with the 15 screw-threaded portion 10 of the follower rod, is secured to and within a sleeve 15 rotatable in and with respect to the casing 1. Means are provided for constraining the said sleeve 15 against longitudinal displacement 20 with respect to the barrel 1. Thus the said sleeve seats or abuts at its lower end against the block 11 and the laterally extending lugs 17 which are secured to said sleeve 15 seat against a cap member 18 screw- 25 threaded or otherwise detachably secured to the casing 1. It will be noted that upper end of the sleeve 15 projects from the casing 1 and may readily be gripped and rotated by the user. The said upper end may be provided 30 with an eraser 19 if desired.

Assuming that the parts are in the position shown in Fig. 1 and it is desired to feed the lead 6 from the pencil, the operator will 35 grasp the projecting end of the sleeve 15 and rotate the same in a clockwise direction with relation to the casing 1. This actuation of the sleeve 15 causes rotation of the nut 16 and consequent longitudinal movement of the rod 9 to force the lead from the pencil 40 to an extent depending on the extent of rotation of said sleeve. To refill the pencil it is only necessary to rotate the sleeve 15 in the reverse direction to retract the rod 9 and the lead may be inserted in the members 2 45 and 3 in a manner now obvious.

The pencil illustrated is also provided with means whereby the user may readily determine the length of lead in the tip portion of the pencil at any time. A shoulder 50 or lug 20 is provided on the follower rod in such a position as to engage the block 11 when a full length crayon 6 is in the tip. The cap 18 is provided with apertures 21 (see Figs. 1 and 2) through which the lugs 55 17 may pass when said lugs and apertures are in registry. By causing such registration the user may pull out the sleeve 15 together with its rod 9 (without removing the cap 18) until the shoulder 20 engages the block 11. It will be appreciated that the 60 extent to which the sleeve 15 may be withdrawn in this manner will be equal to the length of lead or crayon which has been consumed and knowing the normal length 65 of a full size lead the operator will be ap-

prised of the length of lead still available. If desired the sleeve 15 may be provided with calibrations or indicia, to be read with the top of the cap 18 as a reference line, so as to indicate in inches, or other suitable 70 units, the length of crayon in the tip of the pencil. It will be noted that while the lugs 17 are passing the apertures 21 during feeding operation there may be a slight tendency of the sleeve 15 to move out of the barrel. 75 This may readily be avoided by exerting a slight downward pressure on the sleeve 15 while it is being actuated. When the feeding has been accomplished the lugs 17 will be, or may readily be brought, out of registry with the apertures 21 and the parts will then be locked against inadvertent displacement.

The operation and important advantages 80 of my improved pencil will now be apparent to those skilled in the art. I wish also to call attention to the storage spaces 25 and 26 either or both of which may be employed as a magazine for extra crayons.

I claim:

1. In a pencil of the class described, in combination, an outer casing, a tip secured to said casing and provided with an axial bore adapted to receive a crayon, a follower for forcing said crayon through said bore, 95 said follower being externally threaded, means comprising a nut cooperating with the screw threads on said follower for imparting a feed movement to the latter, means actuatable from the exterior of said casing 100 for moving said nut longitudinally away from said tip, and means limiting longitudinal movement of said follower in the last mentioned direction, whereby the amount of movement thus allowed the follower gives 105 an indication of the amount of lead remaining in the pencil.

2. In a pencil of the class described, in combination, a casing provided with means slidably to receive a crayon, a follower within 110 said casing for forcing said crayon from the casing, a head member on said casing, means comprising a part actuatable from the exterior of said casing for imparting a feed movement to said follower on rotation 115 of said part in one direction and for retracting said follower past said head member and without retracting the crayon on longitudinal movement of said part away from said casing.

3. In a pencil of the class described, in combination, a casing provided with a crayon-receiving tip portion, a follower within 120 said casing for forcing said crayon from said casing, a head member on said casing, a sleeve normally within said casing and normally surrounding the upper end of said follower, means constraining said follower against rotation but permitting longitudinal movement thereof with respect to 125

5 said casing, and interengaging means between said follower and sleeve whereby longitudinal movement may be imparted to said follower either by rotation of said sleeve or by longitudinal movement of the latter past said head member and without retracting the crayon.

10 4. A pencil of the class described comprising in combination, a casing provided with a tip through which a crayon is adapted to extend, said tip having a tapering internal bore, an internally bored member screw-threadedly engaging said tip and having a split tapering end adapted to extend into the tapering bore of tip, said member being movable with respect to said casing and means comprising a follower-rod for forcing a crayon through said member.

15 5. A pencil of the class described comprising in combination, a casing provided with a tip through which a crayon is adapted to extend, said tip having a tapering internal bore, an internally bored member screw-threadedly engaging said tip and having a split tapering end adapted to extend into the tapering bore of said tip, means for locking said tip and member against inadvertent relative displacement, and means comprising a follower-rod for forcing a crayon through said member.

20 6. A pencil of the class described, comprising, in combination, a casing provided with a tip through which a crayon is adapted to extend, cooperating screw threads on said casing and tip whereby said tip may be moved toward and away from said casing, said tip having a tapering internal bore, an internally bored member screw-threadedly engaging said tip and having a split end adapted to extend into the tapering bore of said tip, and means comprising a follower-rod for forcing a crayon through said member.

25 7. A pencil of the class described, comprising, in combination, a hollow casing provided with screw threads, a tip through which a crayon is adapted to extend and having screw-threads adapted to cooperate with said first named screw threads to connect said tip and casing, said tip having a tapering internal bore, an internally bored member carried by said tip and having a split end adapted to extend into the tapering bore of said tip, said tip and member being relatively movable in a longitudinal direction, and means comprising a follower-rod for forcing a crayon through said member.

30 8. The invention defined in claim 6 in which means are provided for locking said tip and members against inadvertent relative displacement.

35 9. In a pencil holder, the combination with a tubular body, of a part at the rear thereof providing a shoulder, a nut member rotatable in the body, means in the body movable with respect to said tip, a crayon

forward of the nut member for confining the nut member between said means and the shoulder, said nut member extending through said part, a cap detachably secured to said nut member and positioned externally of the body, a head element detachably secured to the front end of the body, a lead tube therein, a non-rotatable feed screw traversed by the nut and a push rod on the feed screw and engaging in the lead tube. 70 75

10 10. In a pencil holder, the combination with a tubular body, of a nut element rotatable in the rear end thereof, a feed screw engaged by the nut element, means in the body limiting forward movement of the nut element, means on the feed screw engaging with such last named means for preventing rotation of the feed screw, means external of the body for manually rotating the nut element, a head element detachably secured to the body, and providing a lead conduit and a push rod on the feed screw engaging in said lead conduit. 80 85

15 11. The invention defined in claim 7 in which means are provided for locking said tip and member against inadvertent relative displacement. 90

20 12. In a pencil of the class described, in combination, a casing provided with means slidably to receive a crayon, a follower within said casing for forcing said crayon from the casing, means comprising a part actuatable from the exterior of said casing for imparting a feed movement to said follower on rotation of said part in one direction and for retracting said follower on longitudinal movement of said part away from said casing, and means whereby the extent of longitudinal movement of said part depends upon the length of crayon in the tip of the pencil. 105

25 13. In a pencil of the class described, in combination, a casing provided with a crayon-receiving tip portion, a follower within said casing for forcing said crayon from said casing, a sleeve normally within said casing and normally surrounding the upper end of said follower, means constraining said follower against rotation but permitting longitudinal movement thereof with respect to said casing, interengaging means between said follower and sleeve whereby longitudinal movement may be imparted to said follower either by rotation of said sleeve or by longitudinal movement of the latter, and means whereby the extent of longitudinal movement of said sleeve depends upon the length of crayon in the tip of the pencil. 110 115 120

30 14. A pencil comprising in combination, a casing having a removable tip, a sleeve which extends at its opposite ends into said casing and tip respectively when the pencil is assembled, said sleeve being removable through the tip end of said casing when said tip is removed from the casing and being 125 130

- slidably mounted in the bore of said sleeve and frictionally engageable with the wall thereof, and means comprising a follower-rod for forcing the crayon through said sleeve.
15. A pencil comprising the combination set forth in claim 2 and provided with means for limiting the retracting movement of the follower with respect to the casing.
- 10 16. A pencil comprising the combination set forth in claim 3 and provided with means for limiting the longitudinal movement of said follower in the direction toward the head of the casing.
- 15 17. A pencil comprising the combination set forth in claim 14 and provided with means for adjusting the friction between the crayon and the wall of the sleeve by relative rotation of the sleeve and tip.
- 20 18. In a pencil of the class described, the combination with a casing adapted to slidably receive a crayon, of a follower within said casing for forcing said crayon therefrom, a head member on said casing, means comprising a part actuatable from the exterior of said casing for imparting a feed movement to said follower on rotation of said part in one direction and for retracting said follower by an outward longitudinal movement of said part upon said part being turned to a predetermined position relatively to said head member, said longitudinal movement being prevented for other positions of said part.
- 25 19. In a pencil of the class described, the combination with a casing adapted to slidably receive a crayon, of a follower within said casing for forcing said crayon therefrom, a head on said casing, means comprising a part actuatable from the exterior of said casing for imparting a feed movement to said follower on rotation of said part in one direction and for retracting said follower on an outward longitudinal movement of said part, a registerable element on said part and a corresponding registerable element on said head, and means for preventing said longitudinal movement except when said registerable elements are in registry.
- 30 20. In a pencil of the class described, the combination with a casing provided with means slidably to receive a crayon, of a follower within said casing for forcing said crayon therefrom, a head member on said casing, means comprising a part projecting outwardly from said head member for imparting a feed movement to said follower on rotation of said part in one direction and for retracting said follower without retracting said crayon on longitudinal movement of said part away from said casing.
- 35 21. In a pencil of the class described, the combination with a casing provided with a crayon receiving tip portion, of a follower within said casing for forcing said crayon therefrom, a head member on said casing, a sleeve normally within said casing but projecting outwardly from said head member and normally surrounding the upper end of said follower, means constraining said follower against rotation but permitting longitudinal movement thereof with respect to said casing, and interengaging means between said follower and sleeve whereby longitudinal movement may be imparted to said follower either by rotation of said sleeve or by longitudinal movement of the latter without retracting the crayon.
- 40 22. In a pencil of the class described, the combination with a casing provided with means slidably to receive a crayon, of a follower within said casing for forcing said crayon therefrom, a detachable head on said casing, means comprising a part actuatable from the exterior of said casing for imparting a feed movement to said follower on rotation of said part in one direction and for retracting said follower on longitudinal movement of said part away from said casing, without retracting the crayon and without detaching said detachable head.
- 45 In testimony whereof I hereto affix my signature.
- CHARLES F. DOEBLER.
